F. A. WATKINS.
BOOK HANGER AND ADVERTISING DEVICE.
APPLICATION FILED DEC. 3, 1920.

Patented Mar. 28, 1922.

1,410,976.

UNITED STATES PATENT OFFICE.

FREDERICK A. WATKINS, OF CHICAGO, ILLINOIS.

BOOK HANGER AND ADVERTISING DEVICE.

1,410,976.

Specification of Letters Patent. Patented Mar. 28, 1922.

Application filed December 3, 1920. Serial No. 428,098.

To all whom it may concern:

Be it known that I, FREDERICK A. WATKINS, a citizen of the United States, and a resident of Chicago, in the county of Cook and State of Illinois, have invented certain new and useful Improvements in Book Hanger and Advertising Devices; and I do hereby declare that the following is a full, clear, and exact description thereof, reference being had to the accompanying drawings, and to the characters of reference marked thereon, which form a part of this specification.

This invention relates to a novel device having the double function of an advertising medium and a book hanger.

The device, made in accordance with my invention, has been developed more particularly in respect of its function to suspend books which are constantly consulted by the public, such as telephone and like directories; and it is the purpose of the invention to provide an economical, simple and efficient hanger for this purpose that is arranged to be readily adapted to the back-bone of the book in the manner of a clasp so as to securely fix it to the book, and is provided with suspending means whereby it may be suspended from a hook or like support.

In addition to its function as a hanger, the said device is so made as to exhibit a relatively large flap area to receive advertising subject matter. The device, therefore, becomes attractive as an advertising device to be given away in the manner of premiums or other systems that will bring the device free to the user of a directory or other like book, and serves its purpose to suspend the book and to display the advertising subject matter.

In the drawings:

Figure 1 is a perspective view of a portion of a book showing my novel device applied thereto.

Figure 2 is a side elevation of the clasp or hanger in which the invention is embodied, showing it open.

Figure 3 is a fragmentary section on the line 3—3 of Figure 1.

Figure 4 is a perspective detail showing a modified form of jaw or clasp member.

As shown in the drawings, and referring first to Figures 1, 2 and 3, 10, 10 designate the jaw members of the clasp which are hinged to each other near one end of the de-

vice by a pin 11. The said jaws or clasp members are made of thin flat material, such as sheet metal, in order to adapt one of the jaw members to be placed between the leaves of a book near the back thereof, while the other jaw will be displayed along the flat back-bone 12 of the book. In order that the jaws of the clasp may be fixed firmly and reliably in place, when adjusted as shown in Figure 1, with one of the jaw members within the book and the other displayed on the back-bone of the book, the lower ends of said jaws are provided with supporting hooks embracing the in-turned members 13, 13 and upturned terminals 14, 14. The said jaws are hinged to each other to lie in parallel planes so that the supporting hook portions thereof, when the jaws are closed upon each other in place on a book, are adapted to lie in relatively opposing registry with each other, with the up-turned terminal of the hook of one jaw lying against the flat part of the other jaw adjacent said hook, and vice versa, as clearly indicated in Figures 1 and 3.

The upper ends of the jaw members above the hinged pin 11 are formed to provide in-turned members 15, which cross each other at a rather sharp angle in the general manner of the hinge portion of the blades of a pair of shears. In order to provide a suspending member for the clasp, these in-turned portions 15 are continued to form part circular members 16, each of such length that when the device is applied to the back of a book and the lower hook ends are folded one over the other or in registry therewith to support the book, said members 16 overlap at their terminals to constitute a suitably shaped suspending ring or eye designated as a whole by 17.

As shown in said Figures 1 to 3, inclusive, the jaw members 10 are made of equal width. When this practice is followed, each jaw may carry advertising subject matter, with such subject matter displayed on relatively opposing faces of the jaws as is indicated in Figure 2. With this arrangement, it will always be assured that whatever the adjustment of the clasp is to the book, one of the display faces for the advertising will show. Of course, if desired, both sides of each jaw member may carry display subject matter. The advertising matter or display matter will be of a color or tone to sharply contrast it with the faces of the jaw members

of the clasp. Again, one of the jaw members may be made wider than the other to afford more display space, in which event the jaw member that lies between the pages can 5 be made relatively narrower consistent with the strength and durability of the device.

In Figure 4, I have shown a modification in which one of the jaw members 18, between supporting hook and hinge, is made 10 considerably wider than its companion jaw member, which latter is not shown in said figure. In this construction, the wider jaw member is given a quarter twist, so that when the device is in position with one of 15 the jaw members flatwise interleaved with the leaves of the book, the turned portion 19 of the other or display jaw member will lie flatwise against the back-bone of the book. With this arrangement, it is practicable to make the display member of a width 20 substantially the width of the backbone of the book, so as to carry considerably more display or advertising matter.

I claim as my invention:

1. A book hanging clasp adapted to be 25 removably fixed to a book back comprising two elongated supporting jaw members provided at one end of the clasp with inturned, overlapping parts that are hinged together 30 in a plane between the jaw members and formed at said end with a hanger, one of the jaw members being adapted to lie interleaved between the leaves of a book, and the other jaw member being adapted to lie on 35 and unattached to the back-bone of the book, said jaw members being provided at the ends thereof remote from the hanger with inwardly and upwardly turned, overlapping hooks to engage and interlock with the 40 said leaves and back-bone of the book at the bottom thereof, with the upwardly turned part of one of the hooks adapted to lie on the book back-bone and to overlap the other jaw member above its hook to hold one of 45 the jaw members in place relatively to said back-bone.

2. A book hanging clasp comprising two elongated jaw members hinged together near

one end of the clasp, with one of the jaw members adapted to lie interleaved between 50 the leaves of a book, and the other jaw member adapted to lie on, and unattached to, the back-bone of the book, and overlapping, separable, supporting hooks at the free ends 55 of said jaw members at one end of the clasp to cooperate with the jaw members to support a book and to hold one of the jaw members in place on said backbone, the ends of the jaw members at the other end of the clasp being formed with curved portions 60 that overlap to produce a suspending eye.

3. A book hanging clasp comprising two elongated supporting jaw members hinged together near one end, with one of the jaw members adapted to lie interleaved between 65 the leaves of a book, and the other jaw member adapted to lie on and to be free from the back-bone of the book, said jaw members continuing upwardly beyond their hinge connection to form curved terminals that are offset from the planes of the jaw members and are adapted to overlap, when the clasp is closed, to constitute at one end of the device a closed suspending eye, and book interlocking, overlapping members at the other 70 ends of said jaw members.

4. A book hanging clasp comprising two elongated flat sheet metal jaw members hinged together near one end of the device, and provided at the other end of the device with book interlocking supporting members, and so constructed that one of the jaw members is adapted to lie on, but free from, the back-bone of the book when the other jaw member is interleaved between the 80 leaves of the book at the back-bone, and said supporting members being adapted to 85 mutually interlock with each other and the book leaves and back and cooperating with the jaw members when the clasp is closed 90 to support a book.

In witness whereof I claim the foregoing as my invention, I hereunto append my signature this 30th day of November, 1920.

FREDERICK A. WATKINS.
